UNITED STATES PATENT OFFICE.

WARREN C. DRAKE, OF INWOOD, NEW YORK.

FUEL-BURNING METHOD AND FURNACE.

1,391,767.

Specification of Letters Patent. Patented Sept. 27, 1921.

Application filed July 12, 1918. Serial No. 244,656.

To all whom it may concern:

Be it known that I, WARREN C. DRAKE, a citizen of the United States, residing at Inwood, in the county of Nassau and State 5 of New York, have invented certain new and useful Improvements in Fuel-Burning Methods and Furnaces, of which the following is a specification, reference being had therein to the accompanying drawing.

10 This invention comprises a novel fuel burning method and furnace, and relates more particularly to apparatus and method wherein the coal or other fuel is systematically introduced at the feed or front side, 15 a fuel bed being maintained within the furnace, and the fuel being gradually advanced toward the rear or dumping point as it becomes consumed, air being suitably supplied, preferably by forced draft from beneath; 20 the heat resulting from the combustion being utilized for steam boilers, driers, melting or forging plants, or other uses to which a furnace may be put.

The main object of the present invention 25 is to afford a furnace and method which will substantially improve the efficiency and completeness of combustion, consequently increasing the heating results, while effecting a saving of coal and minimizing the production of smoke, as compared with prior furnaces. A secondary object is to make practical and profitable the burning of fuels of low grade, bituminous coals, coals containing a large percentage of ash and other 35 refuse, coals liable to coke from their richness in volatile hydrocarbons, and the like. Further objects are to improve the method 40 of burning the fuel in its progress through the furnace, and the continuous regulation of the operation, to improve the operation of the fuel feed and travel and the regulation thereof, and to improve the supplying of air and its distribution and regulation; also various matters of structure, operation 45 and detail, as will be hereinafter more fully explained.

To the attainment of the above referred to objects, the present invention consists in the mechanical furnace and the method of 50 burning fuel hereinafter illustrated or described, as well as the various features of operation, structure, combination and detail thereof.

In the accompanying drawings, Figure 1 55 is a side elevation, partly in section on the

plane 1—1 of Figs. 2 or 3, of a furnace illustrating and embodying the present invention, with certain well-known and other parts omitted for clearness of illustration.

Fig. 2 is a plan view thereof, partly broken 60 away to show certain particulars.

Fig. 3 is a front elevation, that is, looking toward the left of Figs. 1 and 2, also partly broken away to show details.

Fig. 4 is a side elevation partly in section 65 showing three units or links of the chain-grate on an enlarged scale. Fig. 5 is a top view of the parts shown in Fig. 4. Fig. 6, is a perspective of one of the links of the chain. Fig. 7 is a perspective of one end, 70 of one of the two types of grate bar, and Fig. 8 is a similar perspective of the end of one of the grate bars of the other type shown in Figs. 4 and 5.

Looked at in one way, the present invention 75 novelly combines certain principles heretofore separately known in different types of apparatus. The infeed of coal to a furnace upwardly from a point beneath the fuel bed was *per se* known, for example, in 80 the underfeed stoker patents of Jones 470,052, of March 1, 1892, and Daley 644,664, of March 6, 1900 both expired; and I employ as an element herein a fuel underfeed. The carrying through the furnace of a fuel 85 bed toward the dumping point by a so-called chain grate was *per se* known in such expired patents as Richards 527,454, of October 16, 1894; and I employ as an element herein a chain grate. None of these prior 90 apparatuses, however, nor any others with which I am acquainted, are capable of the mode of operation, the economical method of burning, the efficiency of results or the other advantages pertaining to the present 95 invention. In one aspect I attain the results hereof by employing the principle of underfeed of fuel to a fuel bed which is progressively carried along upon a traveling 100 grate to the dumping point. In a more specific aspect this invention involves a particular combination of the elements or features mentioned, characterized by manner of arrangement, and further features, making highly practical and advantageous the 105 operative result. I believe that no apparatuses or methods heretofore known or attempted in the art operate upon the same principles or by similar particulars as those of the present invention.

It will be noted after reading the below description, that the preferred plan and operation of the present invention as disclosed is that the fuel is forcibly underfed, (by the Jones, Taylor, Riley or other type of stoker), into the front portion of the bed of burning fuel; while therebeyond the bed is bodily carried rearward toward the discharge or dump by a traveling grate which is substantially horizontal, that is, not steep enough to produce avalanching of the fuel, so that the movement is steady. The traveling grate is consecutively beyond the underfeed part of the bed, that is, it follows in substantially uninterrupted succession, so that the fuel bed is unitarily maintained, that is, there is no intermediate avalanching such as would destroy the zones of combustion. The bed may rest on a foregrate to which the underfeed carries it before it passes to the chain grade, and there may be a certain mechanical assistance or agitation at the point of transition to facilitate the advance of the underfed fuel onto the chain grate. Forced draft acts not only upon the underfed portion of the bed, but also upon the portion on the chain grate, extending toward the bridge wall or dump. Less important features will hereinafter appear.

I will now describe in detail the selected embodiment or illustration of the present invention which is shown in the figures of the accompanying drawings. Above a suitable foundation is shown what may be termed the front wall 10 of the furnace, located at the fuel feed or supply side, and opposite thereto, at the rear, is shown a bridge wall 11, but such bridge wall may be absent, depending on the type and purposes of the furnace and its setting or relation to the boiler or other thing to be heated. At the front side of wall 10 is one or a plurality of hoppers 12, the same being in the nature of a chute, into which the supply of fuel is placed which is to be introduced into the furnace. Gravity carries the fuel down to the point where, as will be described, it is forcibly thrust or underfed into the furnace through a throat 13. The fuel bed or mass of coal 14 within the furnace extends from the throat at the front rearwardly to the dumping point, and, as will be explained, the fuel in the bed is humped up at an intermediate point, forming a peak or summit 15. Roughly, and without any clear line of demarcation, the fuel bed may be considered as consisting of substantially three zones. The first zone 16 consists of the green coal before it has taken any part in the combustion. In the second zone 17, beyond that, coking takes place, the coal being converted by the intense heat above and hydrocarbon gases distilled off, which become heat constituents by mixture with the air of combustion and are used fully and completely burned within the fur-

nace, forming an invisible, smokeless, gaseous product. The third or incandescent zone 18 forms the top layer of the fire bed, and is that in which the oxidization of the coal, or rather the coke, is completed, this action continuing progressively along the length of the fire bed, until at the dumping point only ashes, small clinkers and other refuse remain to be discharged into the ash pit 19.

At this point it might be mentioned that an air seal above the ash pit is desirable, and a water-cooled air seal or gate 20 is illustrated as mounted on the bridge wall. This is shown in a somewhat lowered position, but the position may be adjusted externally to accord with the quantity and nature of the discharged material. A perforated pipe 21 provides for small sprays of water, or steam, or other fluid, directed toward and serving continuously to cool the ashes and other material, both before and after the same enter the ash pit. When the fires are banked, the gate 20 can be entirely raised to close the opening between it and the traveling grate to prevent air leakage into the furnace, and the water spray turned off.

Beneath the front of the furnace is shown an air pipe 22, supplied by a blower, or otherwise, and providing a forced air draft through the fuel bed and furnace, although in some cases a natural draft might be sufficient for the purpose. Additional air may be admitted to the furnace through passages 23 at the front, just above the fuel bed, the same supplied by a distributing air box 24, the air flow through which may be regulated in any suitable manner.

As indicated in the plan view, Fig. 2, the entire furnace mechanism consists of a number of longitudinal divisions, which may be termed sections or units, that can be increased in number to any extent, four being shown. A fuel hopper 12 serves for all the sections, and for each section there may be an underfeed mechanism, through which the fuel is forced into one of the front grate portions or troughs, and thence to one of the traveling grates or fuel bed carriers; and the following description will take up these several features in substantially the order mentioned.

The underfeeding mechanism comprises a pusher guide or case 27, exterior to each throat 13 and beneath the hopper 12, and within each pusher case is a pusher or ram 28, adapted to reciprocate toward and from the throat, so that on each retracting stroke coal falls from the hopper in front of the pusher, while on the advancing stroke the coal is thrust through the throat to the under part of the coal bed. As shown, the shape of each throat and pusher is comparatively low or flat, and of maximum width, so that the infeed of fuel takes place

over the greatest possible extent of the total width of the front of the furnace. The trough-like structure inward of each pusher, into which the successive charges are thrust, 5 will be subsequently described. For its actuation the pusher 28 is provided with a rack 29, engaged by driving sector 30, mounted on a rock shaft 31. The toothed sector 30 is shown as extended downwardly below the 10 rock shaft 31 to where it is connected by a shearing pin 32 to a pair of opposed rock arms 32^a keyed on the rock shaft, the purpose of this safety device being that, in case the pusher is blocked, the pin 32 may shear 15 off, rather than allow a breakage in other parts of the mechanism. The rate of fuel infeed may be regulated by altering the rate of action of the pusher, or its throw might be changed by means of a loose connection 20 analogous to the device 72, 73, later described.

An engine or cylinder 33 is shown for actuating the pusher and other parts of the furnace mechanism. The engine piston reciprocates a crosshead 34, and this is connected by a link 35 with an arm 36 on the rock shaft 31, thus reciprocating the pusher as described. Instead of a separate engine for each pusher and grate section, a single 30 engine and a single rock shaft may be used for the entire system. The engine connections to other parts of the furnace mechanism will be subsequently described.

Coming now to the grate system within 35 the furnace, this as a whole may be generally horizontal, and comprises the four or more similar grate sections, as already explained, each of which consists of different portions, as will now be described. What may be 40 termed the foregrate system, or that extending from the furnace front rearwardly to where the traveling grate system commences, provides a fuel bed support which does not travel, but upon which the fuel is underfed 45 by the stoking mechanism described. The foregrate system comprises laterally extending twyer plates or blocks 40, which are shown as overlapping and forming a fuel support extending rearwardly from the 50 lower wall of each throat or fuel entrance 13. The plates 40 may be corrugated, and the overlapping arrangement precludes solid matters sifting downwardly, while the passages or twyers 41 admit air beneath this 55 portion of the coal bed. The longitudinal extent of the foregrate should be sufficient to afford thorough preliminary distillation and heating, so that the combustion of the fuel will surely be completed before the traveling 60 grate system finally discharges the residues into the ash pit.

At the front between each two sections the foregrate preferably comprises an upstanding grate portion 42, constituting a protuberance substantially in line with the division

wall between each two coal entrances or throats 13 and jutting rearwardly into the fuel bed. These protuberant grate portions 42 tend to form troughs between them and to constrain the underfed coal to flow properly into the coal bed, while at the same time, being perforated by twyer passages 43, admit air to the fuel bed above them, thereby maintaining combustion at this portion of the furnace. The foregrate portion 75 formed by the overlapping twyer plates 40 is seen to incline upwardly somewhat from the throat, and owing to this and the fact that the entrance of the coal is at the low level shown, a constant upward motion or flow of 80 the fuel is produced toward the coking and incandescent zones, according to the principle of the underfeed and as indicated in Fig. 1.

The general nature of the movement or 85 flow of the solid fuel through the furnace may now be advantageously described. Under certain conditions of operation it tends to form a high point or peak approximately over where the foregrate meets what may 90 be called the rear grate or traveling grate system, as indicated in Fig. 1. The forcible in-thrust of the underfed coal against the lower part of the inert mass causes the fuel to mount or hump up toward the peak while 95 advancing. Such fuel flow maintains the proper shape of fuel bed, while at the same time every particle of fuel is caused to travel from the green coal zone to and through the coking zone, and thence into the incandescent 100 zone, although the lowermost strata of fuel may not arrive at this zone until well beyond the peak. Beyond the peak the fuel bed progressively decreases in height, due to the speed at which the traveling grates carry 105 it along, and to the fact that the combustion is further and further reducing it to the form of ashes, etc. Generally, the direction of the fuel bed and travel may be approximately level or horizontal, rather than steeply downwardly inclined, and therefore the total operation is free from violence 110 through avalanching of the coal or otherwise. The rearward advancing flow of the fuel is, of course, exceedingly slow and 115 scarcely perceptible, and therefore, although the underfeed pusher is reciprocating and the traveling grates move intermittently by small steps, the operation is for all practical purposes continuous and steady, with the advantage that the ash discharge as well is substantially and automatically continuous, 120 without the disadvantages of periodic-dumping actions.

The above substantially describes the preferred movement of fuel through each section of the furnace with the exception of an agitating action to be described, by which the bed is constantly shaken at the point where the fuel passes from the underfed por- 125

tion to the traveling portion of the grate, that is, substantially beneath the peak of the fuel bed. Additionally, as will appear, the rate at which the different sections of the fuel bed are carried by the respective traveling grate sections varies or differs under suitable control, as will be explained.

The air flow, as stated, is preferably forced, and its general nature, under control, 10 may be as follows. Above the air pipe 22 is a passage 44, with damper 45, leading to the inclosure or chamber below the grate. A front compartment 46 is formed by a vertical division wall 47, which comprises the supporting I-beam shown with plates above and below it, so that the space beneath the foregrate system constitutes a single compartment 46. From the compartment 46 the air under pressure passes upwardly through 20 twyers 41 and 43 into the fuel bed. Beneath the rear or traveling grate system the space may be subdivided into two or more compartments, for example, 48 in the middle, and, at the extreme rear, 49, a division wall 25 50 separating them. From each compartment the air flows upwardly into the fuel bed at the corresponding point. The general direction of the three air streams thus produced is indicated by the elongated arrows or 30 direction lines 51, 52 and 53, respectively.

Control of the air flow may be afforded in the first place by varying the air pressure in the passage 22 through regulation of the blower. In this way the pressure in the front compartment 46 and the air flow through the twyers in the foregrate system may be determined. The pressure and air flow through the middle and rear compartments 48 and 49, and thereby the relative air supply 40 to the front, middle and rear portions of the grate, as a whole, may be regulated by a damper 55 in the division wall 47, and a second damper 56 in the division wall 50. For purposes of illustration the damper 55 is 45 shown opened and the damper 56 closed, under which conditions only the front and middle compartments 46 and 48 will receive air. From the damper 55 extends a control rod 57 to a convenient point in front of the 50 furnace, and likewise from the damper 56 extends a rod 58 with external handle. This damper system gives the possibility of securing universal control as between the front, middle and rear portions of the grate, so 55 that the pressure and supply may be differentially regulated to suit the rate of fuel combustion and other conditions; while at the same time the total air supply and that at each portion of the grate may be proportioned with respect to the rate of fuel supply 60 and combustion, which is very important in securing maximum efficiency in a furnace.

At the point where the advancing fuel passes from the underfed foregrate to the 65 traveling grate system, I prefer to maintain

a slow agitating action, which will be substantially beneath the peak 15 of the fuel bed. I prefer a number of separate agitators, one for each traveling grate. To this end I have shown, located to the rear of the twyer plates 70 40, a rocker 60, notched at its lower side to rest and balance upon the fixed top edge of the partition 47, and provided with transverse grate members or plates 61, 62, with twyer openings 63 between them. By tipping or rocking the agitating member 60 about its described pivot, a slow jogging or settling movement is given to the piled-up coal where it leaves the foregrate system, thus assisting it to descend forwardly and take 80 its place upon the traveling grate system; this action, although not always necessary, is beneficial in the general process of combustion of the fuel bed.

To secure the agitating movement the 85 rocker 60 may be provided with a forwardly extending arm 64, shown connected by a link 65 with an arm 66, secured on a transverse rock shaft, which at a suitable point has a second arm 67 which is connected to an actuating rod 68, which extends forwardly and in turn is connected to a rocker arm 69 on the oscillating power shaft 31. The described connections 64 to 69, inclusive, may be duplicated for each of the four sections of the 90 grate. As will be described, each rod 68 is the same rod through which the corresponding traveling grate is advanced, so that the action of the agitator will be speeded up proportionately to the speed of the grate, as it 100 properly should be. Preferably the bell-crank arm 67 has a loose or yoke connection with the actuating rod 68, there being a collar 71 below it, so that the action is to swing the bell-crank and raise the agitator 105 grate bars 61 and 62, which thereafter descend by gravity upon the return movement of the rod. At the forward end of the rod 68 are adjusting nuts 72 and 73, in front and rear of arm 69. Adjustment of nut 72 alters 110 the extent of up-and-down movement of the agitator, and subsequent adjustment of the nut 73 determines the rate of travel of the 115 grate 75.

I will now describe the traveling grate system from Fig. 1, assisted by the top view Fig. 2, sectional front view Fig. 3, and the structural detail views in the remaining figures. As seen in Figs. 2 and 3, there are four traveling grates 75, and in Fig. 2 two 120 of these are broken open to show the underneath construction. Instead of having the traveling grates in mutually contacting juxtaposition, I prefer to have them somewhat separated, with stationary grate members 125 76 between them, and between the first and last of them and the side walls of the furnace. I prefer to have these intermediate grate portions substantially in line with the foregrate protuberances 42, between which 130

the coal entrance troughs are formed, and I prefer further to arrange other intermediate grate members 77 at a corresponding position between the respective agitator sections 61, 62. By this arrangement each inwardly thrust coal stream passes into and through the trough of the foregrate system, and thence over the agitator, and then the traveling grate, all of which are directly in line. The intermediate grate portions 76 and 77 are relatively narrow, and the portion of the fuel bed thereon will be sufficiently carried along for the purposes hereof. By arching the same, as indicated in Fig. 3, a tendency is produced for the fuel thereon to bear laterally down upon the traveling grates, thus enhancing the advancing movement thereof. The intermediate grate portions 77 between the respective agitators may be composed of overlapping plates similar to the agitators, thus providing twyer openings 63 to supply air between them; and the longitudinal intermediate grate portion 76, which stands between each pair of traveling grates, may be amply provided with air passages 78.

The construction of each traveling grate 75 is generally that an endless series of overlapping transverse grate bars is carried by an endless series of links, which travel along guides and around sprockets, being driven through the shaft of one of the sprockets. Each traveling grate is wholly independent of the others, so that its speed may be independently varied and proportioned to the rate of combustion in that section of the furnace. Before describing the details of each grate, it will be convenient to describe its mode of actuation. As shown in Fig. 1, the forward driving or sprocket shaft 81 is provided with a ratchet wheel 82. Loose on the same shaft is a pawl carrier 83, and to give greater fineness of adjustment, this is provided with two pivoted pawls 84, 84. The oscillation of the carrier causes the pawls to ride back and forth over the ratchet teeth, and each pawl has a counterweight maintaining it in engagement with the ratchet so that the ratchet is given a step-by-step movement as the carrier oscillates. The lower end of each carrier is connected to the rear end of the actuator rod 68, already mentioned. An opening is provided in the division wall 47 to accommodate these parts. Instead of a direct rigid connection between carrier 83 and rod 68, I prefer a yielding connection, so as to give a resilient drive for the purpose of preventing breakage upon the travel becoming jammed. To this purpose the rear end of the rod is surrounded by a coil spring 86, which in turn is surrounded by a barrel 87. The flange or collar at the rear end of the rod bears forwardly on the spring when pulled by the engine, and the

forward end of the spring presses forwardly on the barrel, which is directly pivoted to the carrier. The spring may be rather stiff, so as not to normally appreciably yield. The to-and-fro oscillation of the power arm 69 acting through the rod and carrier causes the pawls to oscillate about the ratchet wheel, and thus give the desired advancing movement to each grate. Regulating the action by the stop screw 72 or the complementary stop screw 73 alters the swing of the carrier and the throw of the pawls to any desired extent.

Since all these described elements 60 to 87 are duplicated for each grate section, the means is provided for independent speed adjustment of the several sections, as already stated. In part the importance of this is due to the tendency in a furnace to burn with irregular or varying intensity at different transverse areas. Thus, near the two side walls the tendency is to burn hotter and faster than in the center, with the result that, if the entire width of grate was adjusted to the same speed to suit the rate of combustion in the middle sections, the combustion in the extreme or side sections would be improper, being too rapid and intense in the first part of travel and the combustion not extending entirely to the dumping point; their places in the bed would occur, and the air would rush in excess quantities through the same, disturbing the combustion over the whole surface. Under such conditions my invention permits the edge sections to be speeded up and the middle sections to be retarded relatively. This complete control of the combustion enables a constant and uniform fire bed to be maintained over the whole interior of the furnace. It gives a gradual and positive, but differential, movement of the fuel bed all the way to the ash pit, so that in each section of the furnace the combustion continues completely to the rear, and is finished at the dumping point. Different fuel conditions may require changes in the adjustment. The described control may be accompanied by a differential control of air flow through the front, middle and rear air compartments and fuel bed, as described. The described principle of forming a peak or high point in the fuel bed by the advantageous underfeed, and then gradually carrying the bed along beyond the peak by the carriers or traveling grates under the described regulation, gives a very advantageous shape of bed, which can be controlled somewhat by relative regulation of underfeed and traveling grate speed, while the greatest efficiency of combustion is attained, no reliance on gravity for the advance is necessary, and the forward movement proceeds throughout the furnace without violence of action. This method of burning the coal has the fur-

ther result of preventing waste because minimizing the amount of combustible remaining in the discharged ashes. At no part of the furnace is the fuel required to be prematurely dumped. The heretofore known underfed furnaces, relying on gravity for travel and resulting in a puddling action, are well known to possess the great disadvantage of forming large clinkers, which is largely or wholly prevented by the present invention, which also permits a substantially steady and continual ash discharge, rather than the disadvantageous periodical dumping operations necessary in the prior apparatuses.

Each traveling grate 75 is preferably the full width of the longitudinal open space between each two intermediate grate portions 76, and may be, for example, approximately 24 inches. Each driving sprocket shaft 81 will be substantially this length, and its ends are supported by bearings 89 held by the stationary vertical supporting walls of the intermediate grate portions 76, as seen in Fig. 3. The front pair of driving sprockets 90, 90, are keyed to the shaft so as to be driven by it and to drive the chain grate. At the rear end each grate is engaged upon a similar pair of idle sprockets 91, 91. A chain grate tightening device for taking up any slack due to expansion or stretching of each chain may be provided, for example, as indicated in dotted lines in Fig. 1. This consists of bearing blocks 92 for the shaft 93 of each rear sprocket, said blocks being longitudinally adjustable in stationary boxes 94. Each block has a threaded stud 95 extending forwardly as indicated, and a threaded collar or nut 96 engages this rod and serves when turned to thrust the sprocket shaft rearwardly to take up slack.

To properly control the air flow against undue loss at the rear, I have shown a rear wall or partition 97 inside the grate structures and approximately above the supporting I-beam 98. At the top of the wall 97 is shown a bent plate or shield 99, the horizontal portion of which bears upwardly against the traveling links by a pressure adjustable through the nut 100. An analogous bent plate 101 bears internally against the returning or lower portion of the traveling grate. A third bent plate 102 is secured on the I-beam 98, and bears upwardly against the lower or exterior side opposite to the plate 101.

The grate itself is built up of two kinds or types of overlapping transverse grate bars 105 and 106, respectively, each corrugated in the manner indicated, so as to provide twyer openings between them. This endless series of grate bars is supported on an endless series of grate links 107, which are shown as being all the same in construc-

tion, and each carrying two of the grate bars. Connecting each pair of links is a pivot stud 108, and the successive studs engage in front of the respective sprockets or projections of the sprocket wheels, as indicated. There are, of course, two opposite chains of links for each traveling grate, and the links and the grate bars carried thereby, as they travel rearwardly, are shown supported against sagging by reason of a guide 75 or flange 110, as more especially seen in Figs. 1 and 3. Each link stud 108 has a roller 109 running on this guide or flange.

The shape of each link 107 is shown in perspective in Fig. 6. It is wider at its rear end, having two ears 112, perforated for the reception of the stud 108, and two ears 113 at the other end spaced less far apart, so as to be capable of being engaged between the ears 112 of the next link, as shown. The body of each link 107 is hollow, and near its rear and front ends, respectively, has cross bars 114, 115, through which the grate bars are secured to the links.

As previously explained, each link has 90 connected to it two grate bars, and the general arrangement can be perceived by examining on Fig. 1 the relative positions of the links and bars as they travel around the sprocket wheel. The grate bar 105 is applied first to the link, see Figs. 4 to 7. This type of grate bar for this purpose has an underhanging lug or hook 117, which, when the grate is assembled, reaches under the link cross bar 115, as clearly shown in Fig. 4. 100 The other type of grate bar 106 has an underhanging lug 118, which engages under the rear cross bar 114 of the link. A recess 119 is provided near the end of each grate bar 105 to accommodate the hook 118 of the 105 overlying grate bar. Analogously the edge of the grate bar 106 is notched at 120 to accommodate the link cross bar 115. To secure the two grate bars rigidly to each other and to the link, a screw 121 is shown passing through a hole 122 in the grate bar 106, and engaged in the threaded hole 123 in the grate bar 105.

Each grate bar is corrugated, as explained, to provide twyer openings between them, 115 and each has at its underside a longitudinal rib 124 for strengthening purposes. The links being all slightly inclined to give the overlapping arrangement shown, each one may have an upstanding end flange 125, giving a generally flat or even edge for the support of the inverted grate bars as they return from the rear to the front of the grate, these flanges 125 bearing on and sliding along a lower guide plate 126, best shown 120 in Figs. 1 and 3.

The traveling grate construction described provides large cooling surfaces to all the portions which bear the fuel bed, and, moreover, every portion of the mechanism which 130

contacts with the fuel is protected against overheating by direct contact with the inflowing cool air. The provision of rollers 109 on the link studs 108 minimizes friction and resistance to the advance of the grate, and thereby prevents warping of the grate bars, which also are prevented from sagging by the fact that the grate bars are not of excessive length, have the strengthening ribs 10 mentioned, and are rigidly locked in place by their inter-engaging lugs. The grate bars are easily removable, interchangeable and replaceable when necessary, and the structure is such that replacement of the 15 grate bars practically renews the furnace, since the links and other supporting parts are protected from undue deterioration.

While I have shown four grate sections, it is obvious that the principles hereof could 20 be employed with a greater or smaller number of sections. Thus, with three separately regulable sections, the middle one could be retarded relatively to the edge ones; while with five or more sections a yet more thorough proportioning of the speed to the rate 25 of combustion at each part of the furnace can be attained. This multiple grate, combined as described with the multiple underfeed means, gives a furnace with controlled 30 infeed and discharge, so that intelligent regulation is possible, permitting the ratio between the infeed and discharge to be made to correspond with the ratio between the total fuel and the incombustible portion 35 thereof. The underfeed, consisting of a plurality of low, wide pushers, gives a stream of entering coal which is as near as possible to the full width of the furnace. The grate protuberances between the fuel entrances are 40 small and narrow, and shaped to secure unification or consolidation of the separate entering streams, so that substantially the full width of the fuel bed flows rearward over the foregrate to where the travel is continued 45 by means of the endless grates. These important features of structure are rendered even more efficient by the introduction of air directly underneath the fuel lying over the foregrate and protuberances, since the distillation and combustion of volatiles is commenced and carried on to a substantial extent before the fuel passes from the foregrate. The present method and machine require no such disadvantageous expedients as 50 have been found practically necessary in heretofore used furnaces. Those furnaces wherein an underfeed was followed by an avalanching overfeed down a steeply inclined grate frequently required, not only 55 the infeed pushers, but supplemental pushers reciprocating at various parts of the fuel bed; all of which resulted in the puddling and avalanching actions already mentioned, requiring a periodically acting dumping 60 grate at the end, and involving the forma-

tion of large clinkers and consequent discharge troubles, beside high loss of combustible matter. Ordinary chain grate furnaces have heretofore been fed by an overfeed hopper discharging directly on top of the fuel bed on the traveling grate, but this has never been of any avail for coking coals, and even on freely burning coals has proven extremely inefficient.

It will thus be seen that I have described a novel fuel burning method and furnace embodying the principles and attaining the advantages of the present invention. Since many matters of procedure, operation, combination, arrangement, structure and detail may be varied without departing from the underlying principles, no limitation to such features is intended except so far as specified in the appended claims.

What is claimed is:

85

1. A fuel burning method comprising forcibly underfeeding fuel into the front portion of the bed of burning fuel and consecutively therebeyond bodily carrying along the fuel bed rearward with substantially horizontal travel toward the discharge.

90

2. A fuel burning method comprising forcibly underfeeding fuel into the front portion of the bed of burning fuel to form and maintain such bed, and therebeyond bodily carrying along the so formed bed rearward with substantially horizontal travel toward the discharge, while applying 95 forced draft through both the underfed and bodily carried portions of the bed.

100

3. A fuel burning method comprising forcibly underfeeding fuel into the front portion of the bed of burning fuel, and consecutively therebeyond bodily carrying along the fuel bed rearward with substantially horizontal travel toward the discharge, while causing forced draft at both the underfed portion and the subsequent bodily carried portion of the fuel bed.

110

4. A fuel burning method comprising maintaining the forebed of burning fuel across the entire width of furnace by underfeeding green fuel into the front side thereof so as to cause rearward travel of the forebed, and consecutively beyond the area of the forebed maintaining and bodily carrying rearwardly the main portion of the fuel bed of substantially greater area than the underfed forebed, while subjecting the same to 115 forced draft.

120

5. A fuel burning method comprising forcibly underfeeding fuel into the front portion of the bed of burning fuel to form and maintain such bed, and consecutively 125 therebeyond bodily carrying along the so formed bed rearward with substantially horizontal travel toward the discharge, the underfeeding and bodily carrying operations being performed with substantial continuity.

130

and at such a rate that the combustion continues substantially to the discharge.

6. A fuel burning method comprising forcibly underfeeding fuel into the front portion of the bed of burning fuel and therebeyond bodily carrying along the fuel bed rearward with substantially horizontal travel toward the discharge, while performing a methodical agitation at the place of transition from the underfed portion to the bodily carried portion of the bed to assist such transition.

7. A fuel burning method comprising forcibly underfeeding fuel into the front portion of the bed of burning fuel, and consecutively therebeyond bodily carrying along the fuel bed rearward with substantially horizontal travel toward the discharge subject to forced draft, and maintaining a differentiation of speeds in different transverse sections of the fuel bed, for example, the edges at faster speeds than the middle, whereby to maintain substantially uniform the combustion in all sections.

8. A fuel burning furnace including in combination, means for forcibly underfeeding fuel into the front portion of the bed of burning fuel, a non-traveling foregrate upon which the underfed fuel is forced and supported, and consecutively to the rear thereof a traveling grate adapted to bodily and steadily carry along the fuel bed rearward toward the discharge.

9. A fuel burning furnace, including in combination, means for forcibly underfeeding fuel into the front portion of the bed of burning fuel, a non-traveling foregrate upon which the underfed fuel is forced and supported, and consecutively to the rear thereof a traveling grate adapted to bodily and steadily carry along the fuel bed rearward toward the discharge; said traveling grate positioned at substantially the level of the underfed foregrate so as to directly receive and substantially horizontally continue the advance of the fuel bed without disrupting its character.

10. A fuel burning furnace, including in combination a non-traveling foregrate of the full width of the fuel bed but less than half the length of the fuel bed, means for forcibly underfeeding fuel upon the entire width of the foregrate, and a traveling grate located directly to the rear of and at substantially the level of the underfed foregrate, adapted to receive and steadily carry along rearwardly the fuel bed.

11. A fuel burning furnace, including in combination, means for forcibly underfeeding fuel into the front portion of the bed of burning fuel, a non-traveling foregrate upon which the underfed fuel is forced and supported, and to the rear thereof a traveling grate adapted to bodily and steadily carry along the fuel bed rearward toward

the discharge, and means for causing forced draft through both the foregrate and the traveling grate.

12. A fuel burning furnace, including in combination, means for forcibly underfeeding fuel rearwardly into the front portion of the bed of burning fuel, and to the rear thereof and substantially at the level of the underfeeding fuel a traveling endless grate adapted to bodily carry and continue the travel of the fuel bed rearward in a substantially horizontal direction from the in-feed toward the discharge.

13. A fuel burning furnace, including in combination, means for forcibly underfeeding fuel rearwardly into the front portion of the bed of burning fuel so as to form the bed into a peak rearward of the fuel entrance, and a traveling endless grate adapted to bodily carry along the fuel bed rearward in a substantially horizontal direction from the fuel peak toward the discharge.

14. A fuel burning furnace, including in combination, means for forcibly underfeeding fuel rearwardly into the front portion of the bed of burning fuel so as to form the bed into a peak rearward of the fuel entrance, and a traveling endless grate adapted to bodily carry along the fuel bed rearward in a substantially horizontal direction from the fuel peak toward the discharge, with air passages beneath the fuel bed provided both in the underfeed portion and the traveling grate portion, and forced draft passages thereto.

15. A fuel burning furnace, including in combination, means for forcibly underfeeding fuel rearwardly into the front portion of the bed of burning fuel so as to form the bed into a peak rearward of the fuel entrance, a traveling endless grate adapted to bodily carry along the fuel bed rearward in a substantially horizontal direction from the fuel peak toward the discharge, and means for methodically agitating the fuel beneath the peak to assist the continued fuel flow between the underfeed and the traveling grate.

16. A fuel burning furnace, including in combination, means for forcibly underfeeding fuel into the front portion of the bed of burning fuel, an air-supplied non-traveling foregrate of substantial extent upon which the underfed fuel is forced and supported, and consecutively to the rear thereof an air-supplied traveling grate arranged to bodily and steadily carry along the fuel bed from the foregrate rearward toward the discharge.

17. A fuel burning furnace, including in combination, means for forcibly underfeeding fuel into the front portion of the bed of burning fuel, an air-supplied non-traveling foregrate of substantial extent upon which the underfed fuel is forced and supported,

- and consecutively to the rear thereof an air-supplied traveling grate arranged to bodily carry along the fuel bed from the foregrate rearward toward the discharge, together with means for methodically agitating the fuel where it passes from the foregrate, to the traveling grate.
18. A fuel burning furnace, including in combination, means for forcibly underfeeding fuel into the front portion of the bed of burning fuel, an air-supplied non-traveling foregrate of substantial extent upon which the underfed fuel is forced and supported, and consecutively to the rear thereof an air-supplied traveling grate arranged to bodily and steadily carry along the fuel bed from the foregrate rearward toward the discharge, together with mechanism for substantially continuously operating said underfeed and traveling grate whereby a rearward fuel flow from the underfeed to the discharge is steadily maintained, with a substantially continuous discharge of ashes.
19. A fuel-burning furnace, including in combination, the front and side walls of the combustion chamber, a bridge wall at the rear thereof, means at the front wall for forcibly underfeeding fuel into the front portion of the bed of burning fuel, a non-traveling foregrate upon which the underfed fuel is forced and supported, and between said foregrate and bridge wall a traveling grate adapted to bodily and steadily carry along the fuel bed rearward from the underfeed to the discharge.
20. A fuel burning furnace, including in combination with the front, bridge and side walls of the combustion chamber, means for underfeeding fuel to the front portion of the fuel bed, and a plurality of separate traveling grates arranged in side by side alinement at substantially the level of the underfeed between the front and bridge walls for bodily carrying the fuel rearward, the length of the several traveling grates being greater than the distance from the front wall to the grates, and means for supplying forced draft to the fuel bed on the traveling grates.
21. A fuel burning furnace, including in combination with the walls of the combustion chamber, means for underfeeding fuel to the front portion of the fuel bed, and a plurality of co-extensive traveling grates arranged side by side at substantially the level of the underfeed for bodily carrying the fuel rearward therefrom to the discharge.
22. A fuel burning furnace, including in combination with the walls of the combustion chamber, means for underfeeding fuel to the front portion of the fuel bed, and a plurality of separate traveling grates arranged side by side for bodily carrying the fuel rearward therefrom, said underfeed-
- ing means comprising a plurality of fuel pushers, each in line with and acting in the direction of travel of one of said traveling grates, a protuberance on the front wall between each two pushers, and a non-traveling longitudinal grate portion in line with each protuberance and extending between each two traveling grates.
23. A fuel burning furnace, including in combination, means for forcibly underfeeding fuel into the front portion of the bed of burning fuel, an air-supplied non-traveling foregrate of substantial extent upon which the underfed fuel is forced and supported, and to the rear thereof an air-supplied traveling grate adapted to bodily carry along the fuel bed rearward toward the discharge, together with mechanism for substantially continuously operating said under feed and traveling grate whereby a rearward fuel flow is steadily maintained and a continuous discharge of ashes, and spraying means for cooling the discharged material.
24. A fuel burning furnace, including in combination, means for forcibly underfeeding fuel into the front portion of the bed of burning fuel, an air-supplied non-traveling foregrate of substantial extent upon which the underfed fuel is forced and supported, and to the rear thereof an air-supplied traveling grate adapted to bodily and steadily carry along the fuel bed rearward toward the discharge; and means for relatively regulating the air supplied to the foregrate and traveling grate, respectively.
25. A fuel burning furnace, including in combination, means for underfeeding fuel to the front portion of the fuel bed, a non-traveling foregrate upon which the underfed fuel is directly received and supported, and a plurality of separate traveling grates arranged at substantially the underfeed level for bodily and steadily carrying the fuel rearward from the foregrate.
26. A fuel burning furnace, including in combination, means for underfeeding fuel to the front portion of the fuel bed, and a plurality of separate traveling endless grates arranged at substantially the underfeed level for bodily carrying the fuel rearward therefrom in a substantially horizontal direction.
27. A fuel burning furnace, including in combination, means for underfeeding fuel to the front portion of the fuel bed, a plurality of separate traveling endless grates arranged side by side at substantially the level of the underfeed for bodily carrying the fuel rearward therefrom toward the discharge, and mechanism for advancing such endless grates at different speeds.
28. A fuel burning furnace, including in combination, means for infeeding fuel to the front portion of the fuel bed, a plurality

- of separate traveling endless grates arranged side by side at substantially the level of the underfeed for bodily carrying the fuel rearward therefrom toward the discharge, and
- 5 mechanism for adjusting the operation in different sections of the furnace to secure different relations respectively between in-feed and discharge.
29. A fuel burning furnace, including in combination, means for infeeding fuel to the front portion of the fuel bed, a plurality of separate traveling endless grates arranged side by side at substantially the level of the underfeed for bodily carrying the fuel rearward therefrom toward the discharge, and mechanism for advancing such endless grates at different speeds, and differently adjusting their speeds to coöperate with rate of combustion at different parts of furnace.
- 20 30. A fuel burning furnace, including in combination, means for underfeeding fuel to the front portion of the fuel bed, a non-traveling foregrate upon which the underfed fuel is directly received and supported, a plurality of separate traveling endless grates arranged side by side for bodily carrying the fuel rearward therefrom, and means for regulating the relative speeds of travel of different grates whereby the edge of the fuel bed may be caused to advance faster than its middle.
31. A fuel burning furnace, including in combination, means for underfeeding fuel to the front portion of the fuel bed, a non-traveling foregrate upon which the underfed fuel is directly received and supported, a plurality of separate traveling endless grates arranged side by side for bodily carrying the fuel rearward therefrom, a non-traveling intermediate grate portion longitudinally between each two traveling grates, and means for regulating the relative speeds of travel of different grates whereby the edge of the fuel bed may be caused to advance faster than its middle.
32. A fuel burning furnace, including in combination, means for underfeeding fuel to the front portion of the fuel bed, and a plurality of separate traveling grates arranged side by side for bodily carrying the fuel rearward therefrom, said underfeeding means comprising a plurality of fuel pushers, each in line with and acting in the direction of travel of one of said traveling grates.
33. A fuel burning furnace, including in combination, means for underfeeding fuel to the front portion of the fuel bed, a non-traveling foregrate upon which the underfed fuel is directly received and supported, and a plurality of separate traveling grates arranged for bodily carrying the fuel rearward therefrom, said underfeeding means comprising a plurality of fuel pushers, each in line with and acting in the direction of travel of one of said traveling grates; and
- travel of one of said traveling grates; and said foregrate comprising an agitator device between each pusher and traveling grate.
34. A fuel burning furnace, including in combination, means for underfeeding fuel to the front portion of the fuel bed, a non-traveling foregrate upon which the underfed fuel is directly received and supported, and a plurality of separate traveling grates arranged for bodily carrying the fuel rearward therefrom; said foregrate comprising an agitator device preceding each traveling grate; and means for regulating independently the speed of travel of different grates and correspondingly the action of each agitator.
35. A fuel burning furnace, including in combination, means for underfeeding fuel to the front portion of the fuel bed, a non-traveling foregrate upon which the underfed fuel is directly received and supported, and a plurality of separate traveling grates arranged for bodily carrying the fuel rearward therefrom; means dividing the beneath-grate space into transverse compartments from which air may pass up through the different grate portions, and air control means for proportioning the air between the foregrate and the traveling grate system.
36. A fuel burning furnace, including in combination, a sectional grate comprising a plurality of side by side grate sections, each section comprising a fuel underfeed entrance portion, followed by agitating means, followed by an endless grate, means for forcibly underfeeding fuel into each entrance, means for advancing the endless grates, and means for relatively regulating the infeeding and advancing means.
37. A fuel burning furnace, including in combination, a sectional grate comprising a plurality of side by side grate sections, each section comprising a fuel underfeed entrance portion, followed by agitating means, followed by an endless grate, means for forcibly underfeeding fuel into each entrance, means for advancing the endless grates, and means for relatively regulating the speeds of different endless grates.
38. A fuel burning furnace, including in combination, a sectional grate comprising a plurality of side by side grate sections, each section comprising a fuel underfeed entrance portion, and an endless grate, a pusher for underfeeding fuel into each entrance, an engine or motor, connections from the engine for reciprocating all the pushers, and connections from the engine for coöperatively causing the advance of all the endless grates, said last named connections having means for adjusting the speeds of different grates relatively to each other and to the pusher operation.

39. A fuel burning furnace, including in combination, means for underfeeding fuel to the fuel bed, and a grate system comprising an endless grate consisting of a plurality of endless chains of links, and an endless series of grate bars arranged to overlap with air passages between, each link

having secured to it a plurality of such overlapping bars, and a bar on each link being overlapped by a bar on another link.

In testimony whereof I have affixed my signature hereto.

WARREN C. DRAKE.
